UNITED STATES PATENT OFFICE.

EDWARD T. BURROWES, OF PORTLAND, MAINE.

DESIGN FOR A GAME-BOARD SUPPORT.

SPECIFICATION forming part of Design No. 34,046, dated February 5, 1901.

Application filed January 4, 1901. Serial No. 42,137. Term of patent 14 years.

To all whom it may concern:

Be it known that I, EDWARD T. BURROWES, a citizen of the United States, residing at Portland, in the county of Cumberland and State of Maine, have invented and produced a new and original Design for a Game-Board Support; and I do hereby declare the following to be a full, clear, and exact description of the same, reference being had to the accompanying drawings, forming a part thereof.

This invention relates to a new and original design for game-board supports; and it consists in the peculiar shape and configuration of the support presently to be described, and shown in the accompanying drawings.

In the drawings, Figure 1 represents a support in perspective. Fig. 2 is an elevation, and Fig. 3 is an end view.

The design comprises, essentially, an oblong block consisting of a base portion A of cylindrical formation, having a flat bottom, the edges *a* of which are slightly rounded. Superimposed on the part A is the cap or head B of cylindrical formation and in diameter that of the part A. The dividing-line

between the parts A and B is indicated by a groove or space C. The length of the part B is less than that of the part A, and the upper portion or top thereof is flat, the edges being slightly curved. On the outer ends of the parts A and B are the raised portions D and E of a diameter slightly less than the parts A and B.

The essential feature of the design is the oblong block consisting of a base portion of 35 cylindrical shape and a top or cap portion of cylindrical shape, the two portions being of uniform diameter and each having flat outer ends and divided by a depression or groove.

Having thus described the invention, what I claim as new, and desire to secure by Letters Patent, is—

The design for a game-board support, substantially as shown and described.

In testimony whereof I affix my signature in presence of two witnesses.

EDWARD T. BURROWES.
